EUGEN IMHOF, OF CANNSTATT, AND ISIDOR HALLE, OF HEILBRONN, GERMANY.

LAST-TESTING TOOL.

1,084,637.

Specification of Letters Patent. Patented Jan. 20, 1914.

Application filed July 14, 1911. Serial No. 638,444.

To all whom it may concern:

Be it known that we, EUGEN IMHOF, a citizen of the Empire of Germany, residing at Cannstatt, in the Empire of Germany, and 5 ISIDOR HALLE, a citizen of the Empire of Germany, residing at Heilbronn-on-the-Neckar, in the Empire of Germany, have invented a new and useful Last-Testing Tool, of which the following is a specification.

Our invention consists of a last testing tool, by means of which the measures of lasts of all kinds can be tested, so that it is possible to select the correct last for shoes and 15 boots of any kind and, if necessary, to correct the last by subsequent working. Then it is possible to produce exactly like shoes and boots.

We will now proceed to describe our invention with reference to the accompanying drawing, in which—

Figure 1 is an elevation of the last testing tool, a last being indicated by dotted lines, Fig. 2 is a plan view of the same, Fig. 3 is 25 an end view of the same, and Figs. 4 and 5 are details, which will be referred to later.

Similar letters of reference refer to similar parts throughout the several views.

A suitable base plate a is provided with a 30 pillar b , on which an arm c can be moved up and down by means of a knob c^1 , a spring of any known construction (not shown) being inserted between the nave of the arm c and the pillar b for producing a soft friction, so 35 that the arm c can be thereby adjusted in any position. In a similar manner a slide f can be vertically adjusted on the pillar b by means of a knob f^1 . The pillar b is provided with a vertical measure b^1 , which is shown to 40 be in millimeters. The nave of the arm c is on the front cut out to form a frame, as is shown, so that it can serve as an indicator on the measure b^1 for adjusting the arm c . Also the front side of the slide f is cut out, 45 so that it serves as an indicator.

In the vertical longitudinal central plane of the pillar b the base plate a is provided with a slot n (Figs. 2 and 5), in which a spring-pressed rabbet o can be moved and adjusted. This rabbet has on it a vertical measure, which is shown to be in millimeters. An exchangeable heel pattern e can be secured in the slide f in any known manner and is made in one with a horizontal plate 50 e^1 for supporting the bottom of the heel of any last, which latter is indicated by the dot-

ted lines. The base plate a is provided with a measure p^1 (shown to be in millimeters) and the rabbet o pushed against the toe of the last serves as an indicator for measuring 60 the length of the last.

On either side of the pillar b is a slotted support x , which can be shifted in a slot w (Fig. 4) in the base plate a and held in adjustment by means of spring-pressed plates x^1 , as is clearly shown in Fig. 4. In the slot of each support x a guide r can be vertically adjusted and held in adjustment by means of a screw r^1 and a nut r^2 . Horizontal rules q and q^1 are longitudinally movable in the guides r and can be secured in any position by means of bent leaf springs s and s^1 fastened on the guides and bearing against the rules. The two rules q q^1 are on their upper surfaces provided with scales v v^1 and carry 70 in their free ends opposite pointers t t^1 of any known construction, which are pressed outward by helical springs u u^1 surrounding them and can be pushed inward against the last for producing marks on the same.

A slide d of a construction similar to f is movable on the arm c and is provided with a vertical fine wire g or the like serving as an indicator. The slide d is made to serve as a guide for a vertical needle h and is on 85 its upper surface provided with a suitable spring i for holding the needle h in any position. As can be seen from Fig. 3, the lower end of the needle h is doubly bent, so as to bring its point into the vertical central 90 plane. The arm c is provided with several scales k l m , which stand in certain proportions to the measure p^1 on the base plate and are made to known rules in use for the principal measures of the last, such as width 95 over the ball (scale k), width over the instep (scale l) and width over the heel (scale m). The scales v v^1 on the rules q q^1 correspond to the scale k .

The last testing tool is operated as follows: In correspondence with the length of any last to be tested a suitable heel pattern e is secured in the slide f and then the last is placed with its middle portion on the base plate a and with its heel on the plate e^1 100 of the pattern e , after which the slide f is vertically so adjusted, that the heel of the last exactly fits the curved recess of the pattern e and its bottom is in close contact throughout with the plate e^1 . Then the 110 rabbet o is pushed against the toe of the last, so that the length of the last can be read off.

the scale p and the height of its toe above the base plate a can be measured on the rabbet o . As the last has marked on it certain measures, it is possible to adjust the 5 slide d on the arm c in accordance with the scale k , so that it occupies the position shown, after which the needle h is moved downward until its point strikes the last and produces thereon a mark. Next the two 10 rules q q^1 are adjusted in such a manner, that one rule, say q for the inner side of a right hand last is adjusted with the aid of its scale v , while the other rule q^1 for the outer side of the last is not positioned quite so far 15 forward as q but is positioned to the rear thereof by three numbers of the scale. Then the two pointers t t^1 are pushed against the last, so as to produce marks on the same. For a left hand last the rule q^1 20 requires to be adjusted in accordance with the scale v^1 and the rule q is put three numbers short of the rule q^1 . When the last is measured over the three marks so produced, the standard width of ball must result, in 25 order to prove the last to be correct. After shifting the needle h upward, the slide d is shifted to the right, so as to bring its indicator g into the plane of the line $y-y$ shown in Fig. 1 in accordance with the scale l for 30 the width of instep, whereupon the needle h is again moved downward for producing a mark on the last. Afterward the needle h is again moved upward and the slide d is shifted to the right for bringing its indicator g into the line $z-z$ in accordance with 35 the scale m for the width of heel and the needle h is moved downward for producing a further mark. Then the last is tested by measuring over the marks produced in the 40 usual manner. With the aid of the new tool it is easy for any one to test any last most carefully and to correct it if necessary.

The last testing tool can be varied without departing from the spirit of our invention.

45 Other measures may be employed instead of millimeters.

We claim:

1. In a last testing tool, the combination with a base plate provided with a slot and 50 having a measure, of a pattern adapted to fit the heels of lasts, means on said base plate for holding said pattern in vertically adjusted position, a rabbet having a vertical measure guided in the slot in said base plate for 55 indicating the length of any last and the height of its toe and horizontally and vertically adjustable means mounted on said base plate for producing marks upon the last.
- 60 2. In a last testing tool, the combination with a base plate having a measure, of a pattern adapted to fit the heels of lasts, means on said base plate for holding said pattern in vertically adjusted position, a rabbet having a vertical measure guided in 65 said base plate for indicating the length of any last and the height of its toe, an arm adjustable on said pillar and provided with scales in various proportions to the measure on said base plate, a second slide adjustable on said

said base plate for indicating the length of any last and the height of its toe, pointers adapted to produce marks on the last, means for vertically adjusting said pointers, and means for horizontally positioning said pointers in various proportions to the length of the last. 70

3. In a last testing tool, the combination with a base plate having a measure, of a pillar on said base plate and provided with 75 a vertical measure, a pattern adjustable on said pillar and adapted to fit the heels of lasts, a rabbet having a vertical measure guided in said base plate for indicating the length of any last and the height of its toe, an arm adjustable on said pillar and provided with scales in various proportions to the measure on said base plate, a slide adjustable on said arm, and a pointer vertically guided in said slide and adapted to 80 produce marks on the last. 85

4. In a last testing tool, the combination with a base plate having a measure, of a pillar on said base plate and provided with 90 a vertical measure, a slide adjustable on said pillar, an exchangeable pattern in said slide adapted to fit the heels of lasts, a rabbet having a vertical measure guided in said base plate for indicating the length of any last and the height of its toe, an arm adjustable on said pillar and provided with scales in various proportions to the measure on said base plate, a second slide adjustable on said arm, and a pointer vertically guided in said second slide and adapted to produce 95 marks on the last. 100

5. In a last testing tool, the combination with a base plate having a measure, of a pillar on said base plate and provided with 105 a vertical measure, a slide adjustable on said pillar, an exchangeable pattern in said slide adapted to fit the heels of lasts, a rabbet having a vertical measure guided in said base plate for indicating the length of any last and the height of its toe, two supports 110 adjustable in said base plate, there being one of said supports on each side of said pillar, two guides vertically guided on said two supports, two horizontal rules guided in said two guides and provided with scales in a 115 proportion to the measure on said base plate, and two pointers at the ends of said two rules adapted to produce marks on the last.

6. In a last testing tool, the combination with a base plate having a measure, of a pillar on said base plate and provided with a vertical measure, a slide adjustable on said pillar, an exchangeable pattern in said slide adapted to fit the heels of lasts, a rabbet having a vertical measure guided in said base plate for indicating the length of any last and the height of its toe, an arm adjustable on said pillar and provided with scales in various proportions to the measure on said base plate, a second slide adjustable on said 120 125 130

arm, a pointer vertically guided in said second slide and adapted to produce marks on the last, two supports adjustable in said base plate, there being one of said supports on each side of said pillar, two guides vertically guided on said two supports, two horizontal rules guided in said two guides and provided with scales in a proportion to the

measure on said base plate, and two pointers at the ends of said two rules adapted to produce marks on the last.

EUGEN IMHOF.
ISIDOR HALLE.
